UNITED STATES PATENT OFFICE

HENRY C. TRAUT, OF MONMOUTH BEACH, NEW JERSEY, ASSIGNOR TO THE DIAMOND MATCH COMPANY, OF CHICAGO, ILLINOIS, A CORPORATION OF ILLINOIS

COMBINED MATCH BOOK AND GOLF TEE HOLDER

Application filed August 13, 1929. Serial No. 385,522.

This invention relates to a combined match book and golf tee holder; my object being to provide a simple, compact and efficient device wherein a cellular receptacle is associated with the foldable cover of a match book in such relation thereto that the shanks of golf tees are easily insertable in the receptacle in alternate order from opposite edges of the cover, and that the enlarged heads of the inserted tees overlie the opposing surface of the cover and bear forcibly thereagainst, thereby frictionally holding the shanks of the tees within the receptacle until the tees are severally withdrawn for use, as will be hereinafter described and claimed.

In the drawings—

Figure 1 is a rear elevation, partly in section, of a match book and golf tee holder embodying my invention.

Fig. 2 is a vertical section of the device, as on the line 2—2 of Fig. 1.

Fig. 3 is an end view of the same.

Fig. 4 is a perspective view of the device.

Referring to the drawings, A designates a match book of any usual or approved construction, the same in the present instance comprising a flexible pasteboard cover 5 and card matches 6 whereof the uncut base portions 7 are embraced by and secured to a short fold 8 at one end of the body of the cover.

According to my invention I secure, by gluing for example, on the outer side of the cover body 9 a cellular receptacle B for golf tees C, which receptacle is of rectangular form and of less length and width than the cover body. This receptacle comprises preferably a strip 10 of corrugated pasteboard interposed between layers 11 of paper, or other suitable material, the whole being surrounded by a paper wrapping 12, thereby providing a plurality of parallel cells, whereof each is designed and proportioned to receive the shank of a tee. The cellular receptacle is so positioned on the cover that the cells extend transversely of the latter with their

open ends spaced from the adjacent edges of the cover a distance substantially equal to the depth of the enlarged beveled head of a tee. Hence when the shank of a tee is inserted in any of the cells the beveled head of the tee overlies the opposing surface of the cover and bears forcibly thereagainst, thereby frictionally clamping the shank against the wall of the cell and retaining the tee securely in place until it is withdrawn for use.

As the receptacle B is spaced from the longitudinal edges of the cover, the golf tees are insertable in the cells in alternate order from opposite edges of the cover, thus ensuring the compact assembly and retention of two rows of tees, as shown, and at the same time exposing the heads of the tees to permit the easy and convenient withdrawal of each individual tee.

A convenient score card may be printed upon the flap of the match book cover, if desired.

I claim—

1. A device of the character described consisting in the combination with a flexible match book cover, of a golf tee holder attached to the outer surface of said cover, said tee holder having a plurality of parallel cells extending transversely of the cover and being spaced at their open ends from the respective longitudinal edges of the cover, whereby the shanks of the tees are insertable in the cells in alternate order from opposite edges of the cover in such manner that the heads of said tees will overlie the opposing surface of the cover and bear forcibly thereagainst, thus frictionally clamping the shanks of the tees within the respective cells.

2. A device of the character described consisting in the combination with a flexible match book cover, of a golf tee holder attached to the outer surface of the cover, said holder including a strip of corrugated material and providing a plurality of parallel cells extending transversely of the cover and

being spaced at their open ends from the respective longitudinal edges of the cover, whereby the shanks of the tees are insertable in the cells in alternate order from opposite edges of the cover in such manner that the heads of said tees will overlie the opposing surface of the cover and bear forcibly thereagainst, thus frictionally clamping the shanks of the tees within the respective cells.

10 Signed at New York, in the county and State of New York, this 12th day of August, A. D. 1929.

HENRY C. TRAUTE.
